H. HUNT.

CARPET.

No. 17,681.

Patented Sept. 6, 1887.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 17,681, dated September 6, 1887.

Application filed July 21, 1887. Serial No. 244,939. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The main feature of my design is the figure A, which has a border of shadow-work, more or less regularly repeating the outline of the

main body of the figure. The figure A is a conventionalized leaf form with a deeply-indented edge. The shadow-work is prominent and plainly distinguished from the central figure it surrounds. Similar leaf figures with similar shadow-work complete the design.

What I claim as new, and desire to secure by Letters Patent, is—

1. The design for carpets, consisting of the arc-shaped figure A, substantially as shown.
2. The design for carpets, consisting of the figure A and the other figures, substantially as shown.

HENRY HUNT.
